UNITED STATES PATENT OFFICE.

WILLIAM D. MARKS, OF PHILADELPHIA, PENNSYLVANIA, ASSIGNOR TO THE AMERICAN ELECTRIC METER COMPANY, OF SAME PLACE.

ELECTRIC METER.

SPECIFICATION forming part of Letters Patent No. 595,325, dated December 14, 1897.

Application filed September 10, 1897. Serial No. 651,219. (No model.)

To all whom it may concern:

Be it known that I, WILLIAM D. MARKS, a citizen of the United States, residing at Philadelphia, county of Philadelphia, and State of Pennsylvania, have invented a certain new and useful Improvement in Electric Meters, of which the following is a specification.

This invention relates to the circuit-controller for the oscillating electric motor of electric meters of the character shown in Letters Patent No. 571,032, issued November 10, 1896; and the main object of my invention is to insure a more perfect and uniform contact at the circuit-controller than was heretofore obtained.

I have found that when a number of meters of the character referred to were set up and operated the oscillations of the pendulums varied to a considerable extent, owing to the fact that the contacts of the circuit-controllers did not all make perfect and uniform contact, resulting in incorrect registration. I have obviated this difficulty by providing a device which will insure the contact-pins of the overbalanced circuit-controllers making contact with the contact-plate carried by the pendulum or other member at a uniform point and produce a good rubbing contact, thereby maintaining clean contact-surfaces. Several forms of such devices have been devised by me, some of which are illustrated in the accompanying drawings, in which—

Figure 1 is a general elevation indicating the essential parts of the meter and one of the preferred forms of my "contact-controller," which is the term I will use in referring to my device for insuring perfect and uniform contact at the circuit-controller. Fig. 2 is an enlarged view of the contact-controller shown in Fig. 1; and Figs. 3 to 9, inclusive, illustrate modified forms.

Referring to Fig. 1 of the drawings, A indicates the coil of the ampere-indicator; B, the core, which actuates the pointer C and the controlling cam or arch D. The arch D controls the position of the driving-lever E, which carries the pawl e, engaging with the first wheel F of the register. Lever E is actuated by the oscillating cam G, secured to the arbor of the oscillating motor or pendu-

lum H, which is provided with a core or armature h, actuated by the coil I.

The circuit-controller comprises an arm J, pivoted eccentrically to the cam G and carrying a contact-pin J', which makes contact 55 with a plate K, carried either by the arm of cam G or by a separate support mounted on the arbor of the pendulum. The arm J is overbalanced by an adjustable weight J².

L is a guard of insulating material secured 60 to the arm of cam G or to the support for plate K when a separate support is employed. This guard has an opening into which the pin J' projects.

The position of the parts in Fig. 1 represent 65 the meter at rest—that is, the pin J' and plate K are in contact, but the circuit in which the meter is located is open. When the circuit to the meter is closed and current passes through coil I, the pendulum swings first to- 70 toward the coil, causing the cam G to swing to the right, which through the engagement of contact-plate K and pin J' moves arm J also to the right. As the arm J is carried over its center of gravity it topples over independently 75 of the movement of the cam G or the part carrying the contact-plate K, thus removing the pin J' from contact with plate K and opening the circuit to coil I. On the return or back- 80 ward swing of the pendulum (during which the cam G actuates the register-lever E) the guard L moves with the cam to the left and carries the arm J also to the left, the pin J' during this movement working down the right-hand edge of the guard. When the cam and guard 85 are near their central positions, the arm J will be again carried over its center of gravity and caused to topple over to the left; but in this position of the cam and guard the pin J' will strike against the left-hand edge of the 90 guard below the contact-plate K, due to the arm being pivoted eccentrically to the cam. As the cam and guard continue to move to the left the pin J' moves upward on the left edge of the guard, and when the cam and 95 guard reach the position of Fig. 1 the pin J' will be in contact with plate K and the circuit to coil I will be again closed. The circuit is held closed until the arm J topples over again to the right, as above stated. Thus it will be 100

seen that the motor-circuit is closed for a short period during the last half of each forward swing of the pendulum, causing a slight impulse to be imparted to the pendulum at 5 regular intervals and of equal duration, thus maintaining a uniform rate of oscillation. In practice, however, I have found that the regularity and duration of contact at the circuit-controller is apt to vary, due to unclean 10 contact-surfaces, vibration, or other causes. To obviate this difficulty, I provide the contact-controller.

The form of contact-controller shown in Figs. 1 and 2 is substantially an L-shaped 15 metal plate M. The arm m is provided with a hole for a pivot-pin by which the plate is pivoted to the cam G, as seen in Fig. 1. The long arm of the plate has a finger m', which bears against the inner side of the arm of 20 cam G. Below finger m' is an oblique flange m², projecting outward at right angles to the plate. This flange is normally held against contact-plate K by a spring m³, Fig. 1, fixed in a slot in the underside of cam G and whose 25 free end bears against the flange m⁴, projecting from the long arm of the plate M. The flange m² is designed to engage contact-pin J' and force it against the contact-plate to produce a good rubbing contact when the pin 30 moves upward on plate K. As contact-pin J' clears the upper edge of the oblique flange m² the arm J is free to fall over to the left, as above described.

In the construction shown in Fig. 3 the contact-controller is secured to the free end of spring m³ instead of being pivoted to the cam. In this form I provide a finger m' and oblique flange m², as in the form shown in Fig. 2, and I also provide an arm x, which bears 40 against the hub of cam G for limiting the movement of flange m² toward the contact-plate K, although this arm is not essential.

In Figs. 4 and 5 I show a spring S, bent, as shown in Fig. 4, (which gives an edge view 45 of the spring,) to form an oblique flange m² for forcing the contact-pin J' against plate K. Spring S also has a bend at right angles, as seen in the face view, Fig. 5, to afford a clearance for pin J' and permit it to topple 50 over, as above described.

The form shown in Figs. 6 and 7 is preferred when it is desirable to make the contact-plate K and contact-controller readily removable for repair or inspection. In this 55 form a separate arm N is provided for coöperating with the circuit-controller. This arm is designed to be secured to the arbor of pendulum H in front of the cam G. The arm is cut away, as shown by dotted line n n, and 60 a head O is fitted to the arm and secured by a screw o, passing through flange o' into the upper end of arm N. The end of the downwardly-extending arm O' of head O is beveled, as shown, so as to fit the cut n'. Contact- 65 plate K is secured to arm O'. P is a plate pivoted at p to head O, and this plate at the lower end is provided with a block p', hav-

ing a beveled surface m², Fig. 6, which performs the same function as the oblique flange m² of the constructions shown in Figs. 2, 3, and 70 4. At the top plate P has a finger p', against which bears the spring m³, which forces block p' against contact K. To remove contact-plate K and the contact-controller, it is only necessary to remove screw o, when the entire 75 device may be removed from the supporting-arm N.

In Figs. 8 and 9 I have shown another form of contact-controller mounted upon a separate supporting-arm N. In this form the 80 spring m³ is secured at its upper end to a plate Q, which is secured upon the upper end of arm N. The lower end of spring m³ is bent outwardly and has secured to it a plate m², which corresponds to the oblique flange 85 m² of the form shown in Figs 2 to 5, inclusive. Spring m³ is also provided with a finger m', which bears against the inner side of supporting-arm N.

The guard L in each form has a clearance 90 at the edge adjacent to the contact-plate K, in order to permit good contact between plate K and pin J'.

From the foregoing it will be seen that contact-pin J' will be forced into contact with 95 plate K at a uniform point, and the pressure of the spring will produce a good rubbing contact, which will also result in clear and bright contact-surfaces.

What I claim is—

1. In an electric meter, the combination with an oscillating electric motor or pendulum and an oscillator actuated thereby for driving a register, of a circuit-controller for periodically opening and closing the motor-circuit, comprising a contact-plate carried by the oscillator, a second contact pivoted to a stationary support eccentrically to the oscillator and capable of movement independently of the oscillator, and an insulating-guard on said oscillator for limiting the movement of said pivoted contact, substantially as and for the purpose set forth. 100

2. In an electric meter, the combination with an oscillating electric motor or pendulum and a pivoted driving device for operating a register, of a circuit-controller for periodically opening and closing the motor-circuit, comprising a contact-plate carried by the driving device, a second contact carried by 115 an overbalanced arm pivoted to a stationary support eccentrically to the driving device and capable of movement independently of the driving device, and an insulating-guard on said driving device for limiting the movement of said pivoted contact, substantially as and for the purpose set forth. 120

3. In an electric meter, the combination with an oscillating electric motor or pendulum and a pivoted driving device for operating 130 a register, of a circuit-controller for periodically opening and closing the motor-circuit, comprising a contact-plate carried by the driving device, a pin projecting into the path

- of movement of said driving device and adapted to make contact with said plate, said pin being carried by an arm pivoted to a stationary support eccentrically to the driving device and capable of movement independently of the driving device, and a guard for limiting the movement of said pivoted contact-pin, substantially as and for the purpose set forth.
- 10 4. The combination with a circuit-controller having two relatively movable contacts adapted to periodically open and close a circuit, of a device coöperating therewith for maintaining regularity and proper duration 15 of contact at the circuit-controller, substantially as set forth.
5. The combination with a circuit-controller having two relatively movable contacts adapted to periodically open and close a circuit, of a device held under spring-pressure coöperating with said contacts for maintaining regularity and proper duration of contact at the circuit-controller, substantially as set forth.
- 20 6. The combination with a circuit-controller having two relatively movable contacts adapted to periodically open and close a circuit, of a pivoted arm having a projection in the path of movement of one of said contacts 25 for forcing said contact against the other contact at a uniform point, substantially as set forth.
7. In an electric meter, the combination with an oscillating electric motor or pendulum, of a circuit-controller for periodically opening and closing the circuit, comprising 30 a contact-plate movable with the pendulum, a second contact pivoted eccentrically to the pendulum and capable of movement independently of the pendulum to periodically open and close the circuit, an insulating-guard for limiting the movement of said pivoted contact, and a device coöperating with the circuit-controller for maintaining the regularity and proper duration of contact at the circuit-controller, substantially as set forth.
- 35 40

open and close the circuit, and a device co-operating with the circuit-controller for maintaining the regularity and proper duration of contact at the circuit-controller, substantially as set forth.

8. In an electric meter, the combination with an oscillating electric motor or pendulum, of a circuit-controller for periodically opening and closing the circuit, comprising a contact-plate movable with the pendulum, 45 a second contact carried by an overbalanced arm pivoted eccentrically to the pendulum, and capable of movement independently of the pendulum to periodically open and close the circuit, and a device coöperating with the 50 circuit-controller for maintaining the regularity and proper duration of contact at the circuit-controller, substantially as set forth.

9. In an electric meter, the combination with an oscillating electric motor or pendulum, of a circuit-controller for periodically opening and closing the circuit, comprising a contact-plate movable with the pendulum, 55 a second contact carried by an overbalanced arm pivoted to a stationary support eccentrically to the pendulum and capable of movement independently of the pendulum to periodically open and close the circuit, an insulating-guard for limiting the movement of said pivoted contact, and a device coöperating with the circuit-controller for maintaining the regularity and proper duration of contact at the circuit-controller, substantially as set forth.

This specification signed and witnessed this 75
8th day of September, 1897.
